UNITED STATES PATENT OFFICE.

AUGUST BEHRENS, OF GRAND RAPIDS, MICHIGAN.

DESIGN FOR A HINGE.

SPECIFICATION forming part of Design No. 30,022, dated January 17, 1899.

Application filed December 20, 1898. Serial No. 699,870. Term of patent 14 years.

To all whom it may concern:

Be it known that I, AUGUST BEHRENS, a citizen of the United States, residing at Grand Rapids, in the county of Kent and State of Michigan, have invented and produced a new and useful Design for Hinges, of which the following is a specification, reference being had to the accompanying drawings, forming part thereof.

Figure 1 is a plan of my hinge. Fig. 2 is an edge, and Fig. 3 is an end, view of the same.

As shown in the drawings, the leading or material feature of my design consists of two long narrow wings A, pivoted together, the edges thereof being beveled, as at a, in one di-

rection, so that the lower or back surface of the wings will be broader than the front or upper surface and the wings meeting with a deep shoulder back of the pivot, as at b.

Having thus fully described my design, what I claim as new, and desire to secure by Letters Patent, is—

The design for a hinge herein described and shown.

Signed at Grand Rapids, Michigan, December 13, 1898.

AUGUST BEHRENS.

In presence of—

D. W. KENDALL,
ITHIEL J. CILLEY.
